KNOCKDOWN CHAIR

Henricus J. J. Wagemans, Maastricht, Netherlands, assignor to Wagemans & Van Tuinen N. V., Maastricht, Netherlands, a corporation of the Netherlands

Application September 23, 1955, Serial No. 536,101

5 Claims. (Cl. 155—191)

This invention relates to an improvement in knock-down or collapsible chairs for home, shipboard, beach, business and other purposes.

There is a substantial demand for attractive and comfortable chairs which can be knocked down or collapsed into a small space for storage, shipment or other transportation, but which can be quickly and easily assembled when needed and which, when assembled, provide a comfortable and attractive chair.

Most chairs of the folding, collapsible or knockdown type are difficult to assemble, often requiring the use of tools for this purpose. They are uncomfortable to sit on. They are usually of weak or flimsy construction and their appearance is such that they are only suitable for beach, picnics and other outdoor purposes.

It is one of the objects of my invention to provide a knockdown chair in two parts which is easy to assemble or disassemble and which when assembled provides an attractive piece of furniture which is comfortable to sit on.

Another object of my invention is to provide a knock-down two-part chair which is of sturdy construction and in which the parts are automatically locked and held in position when the chair is assembled.

Another object of my invention is to provide a knock-down two-part chair which can be upholstered in attractive fabrics and provide a chair suitable for use in the living room of a home, a hotel lobby or other places where an attractive appearance and sturdy construction is desired.

Another object of my invention is to provide a two-piece knockdown chair, which when knocked down or collapsed, can be easily handled and occupies only a small space for shipping, storage or other purposes.

Various other objects and advantages of my invention will appear as this description proceeds.

Referring now to the drawings which illustrate a preferred form of embodiment of the invention,

Fig. 1 is a perspective view of an assembled upholstered chair constructed according to my invention;

Fig. 2 is a sectional view through the locking construction of the chair with the upholstering removed;

Fig. 3 is a plan view of the seat and rear leg frame construction of the chair;

Fig. 4 is a plan view of approximately one half of the back and front leg frame construction of the chair, and

Fig. 5 is a perspective view of an upholstered chair illustrating the parts in the processes of disassembly.

In the form of embodiment of the chair illustrated in Figs. 1 and 5, the chair consists of a back portion A to which the front legs A¹ and A² are secured, forming one complete part of the chair, and of a seat portion B to which the rear legs B¹ and B² are secured, forming the other part of the chair. The back portion A and the seat portion B, and the front and rear legs connected thereto, are made as separate units of the chair, as illustrated in Fig. 5, which are assembled and

2

locked together to form the complete chair as illustrated in Fig. 1. The back portion A and the legs A¹ and A² connected to it and seat portion B and the legs B¹ and B² connected to it may be readily separated for storage or shipment and again assembled together and locked in their assembled relation by simple movement of the two parts of the chair and without the use of tools.

Referring now to Fig. 2 which illustrates a preferred form of locking construction, the back portion A, with the legs A¹ and A² connected thereto, has two spaced horizontal rails 3 and 4 extending between the legs A¹ and A² and connected to the legs A¹ and A² in any suitable manner. Preferably, the upper rail 3 is connected at each end by dowels, shown in dotted lines, and, by gluing to the leg portions A¹ and A² and the lower rail 4, is connected to the legs A¹ and A² at each end in a similar manner. Corner brackets 4^a are also secured in the corners between the lower rail 4 and its adjacent legs A¹ and A².

The lower rail 4 is of substantially rectangular shape but the upper corner 4^b is cut on an angle as illustrated to facilitate passing the rear legs, connected to the seat portion B, between the upper and lower rails 3 and 4 of the back portion and to provide a flat supporting surface 4^b for the seat portion when the two parts are in assembled position. In the assembled chair the flat supporting surface 4^b lies in a substantially horizontal plane.

The upper rail 3 is cut on a diagonal 3^a to provide a flat upper bearing surface for the seat B and rear legs B¹ and B². The face 3^a lies in a substantially horizontal plane when the parts of the chair are in assembled position.

Means are provided for locking the parts of the chair in assembled position. For this purpose, the center of the upper rail 3 is provided with a slot 3^b into which a locking dowel block 5 is secured to lock the parts of the chair in assembled position as described later. A plywood or other back support A⁴ is secured to the upper rail 3 and upper portion of the legs A¹ and A² and serves as a support for the springs and upholstery used for upholstering the back portion as illustrated in Figs. 1 and 5. The springs, upholstery, etc. may be applied to the back portion A in any desired manner and the details of the upholstering form no part of the present invention.

The seat portion B consists of the seat support B³ which may be of plywood or the like, connected to leg portions B¹ and B², and a yoke member 6 extending between the legs B¹ and B² and connected to each leg B¹ and B² by dowel and glue connections similar to the way the rails 3 and 4 of the back portion are connected to the legs A¹ and A². The yoke 6 is given a slight curvature on its rear face as shown at 6^b and has flat top and bottom faces. When the parts of the chair are in assembled position, the bottom face of the yoke 6 and a portion of the plywood seat portion B³ rests upon the diagonal face 4^b of the lower rail 4 and the top face of the yoke 6 rests against the corresponding face 3^a of the upper rail 3. A slot 6^a in the top of the yoke 6 receives the projecting end of locking dowel block 5 to lock the seat and back portion of the chair in assembled position and a layer of felt 7 secured to the bottom of the upper rail 3 of the back portion provides a noiseless connection between the back and seat portion of the chair.

A curved upholstery support bar 8, secured to the leg portions B¹ and B² and the yoke 6, is shown in Fig. 2. The seat portion is provided with springs, padding and upholstery as illustrated in Fig. 1, but as the manner of applying the upholstering is not a part of the present invention it will not be further illustrated and described.

The assembled position of the seat and back portion

is illustrated in Figs. 1 and 2. In this position the chair provides a firm and steady seat with the ends of the four leg portions A¹, A², B¹ and B² resting on the floor and preventing tipping of the chair in any direction. In use, the position of the yoke 6 on the upper and lower rails 3 and 4 tend to wedge the parts together when a person is sitting in the chair, so that a firm locking is provided without the locking dowel block 5, which can, if desired, be omitted. With the locking dowel block 5 in position, the parts of the chair cannot accidentally become separated. In place of the dowel block 5 and slot 6^a, other cooperating blocks or lugs and grooves may be provided in the faces of the yoke 6 and rails 3 or 4 to lock the parts in assembled position.

In order to separate the parts of the chair for storage, shipment or other purposes, the back portion A is tipped forward and the seat is lifted upward so that rear leg portions B¹ and B² are turned in a clockwise direction substantially around the face 4^b of the lower rail 4 as a center, as indicated by the arrow 9 (Fig. 2) until the slot 6^a clears the projecting end of the locking dowel block 5 whereupon the seat portion B and legs B¹ and B² may be moved forward, as illustrated in Fig. 5, to pull the legs B¹ and B² from the rectangular space defined by the legs A¹ and A² and the rails 3 and 4 and separate the seat and back portion of the chair. When separated, the back portion, consisting of the upholstered back A and connected legs A¹ and A², and the seat portion, consisting of the upholstered seat B and connected legs B¹ and B² may be stacked one on top of the other, or in any other desired position, so that they occupy a very small space for storage or shipment of the chair. No tools are needed to assemble or disassemble the two parts of the chair and there are no loose parts to be removed and nothing which might become lost.

While I have illustrated and described a preferred embodiment of my invention, consisting of an upholstered chair, it will be understood that the upholstering may be omitted and a simple frame chair provided, and that various other modifications and changes may be made from the chair as illustrated without departing from the spirit of my invention or the scope of the following claims.

I claim:

1. In a knockdown chair of the type described, a back portion having two legs connected thereto, a seat portion having two legs connected thereto, spaced rails extending between the legs of the back portion and connected thereto, a rigid yoke member extending rearwardly from the seat portion between the legs of the seat portion and connected to the seat portion and to the legs of the seat portion, the legs and yoke of the seat portion occupying a position between the rails and legs of the back portion when the chair is in assembled position and the top of the yoke member bearing against the upper rail extending between the legs of the back portion.

2. In a knockdown chair of the type described, a back portion having two legs connected thereto, a seat portion having two legs connected thereto, spaced rails extending between the legs of the back portion and connected thereto, each of said rails having a diagonal flat face extending in a substantially horizontal plane when the chair is in assembled position, a rigid yoke member extending rearwardly from the seat portion between the

legs of the seat portion and connected to the seat portion and to the legs of the seat portion, the legs and yoke of the seat portion occupying a position between the rails and legs of the back portion with the yoke resting against the diagonal faces of said rails when the chair is in assembled position, and a noise proofing material between said yoke and one of said rails.

3. In a knockdown chair of the type described, a back portion having two legs connected thereto, a seat portion having two legs connected thereto, spaced rails extending between the legs of the back portion and connected thereto, each of said rails having a diagonal flat face extending in a substantially horizontal plane when the chair is in assembled position, a yoke member extending between the legs of the seat portion and connected thereto, the legs and yoke of the seat portion occupying a position between the rails and legs of the back portion with the yoke resting against the diagonal faces of said rails when the chair is in assembled position, a locking means secured in one of said rails and projecting from the diagonal face thereof and a slot in said yoke for receiving said locking means.

4. In a knockdown chair of the type described, comprising essentially two separable parts, one part consisting of a back portion having two legs connected thereto, the other part consisting of a seat portion having two legs connected thereto, spaced substantially rectangular rails extending between the legs of the back portion and connected thereto, a flat diagonal face on each of said rails, said flat diagonal faces lying in spaced substantially parallel horizontal planes when the chair is in assembled position, locking means secured to one of said rails, a yoke member extending between the legs of the seat portion and connected thereto, said yoke member having upper and lower faces lying in spaced substantially parallel horizontal planes when the chair is in assembled position, a locking means receiver in said yoke, the legs and yoke of the seat portion occupying a position between the rails and legs of the back portion when the chair is in assembled position, with the locking means locking the parts in assembled position.

5. In a knockdown chair of the type described, an upholstered back portion having two legs connected thereto, an upholstered seat portion having two legs connected thereto, spaced rails extending between the legs of the back portion and connected thereto, said rails having opposed faces extending in a substantially horizontal plane when the chair is in assembled position, a yoke member extending between the legs of the seat portion and connected thereto, the legs and yoke of the seat portion occupying a position between the rails and legs of the back portion with the yoke resting against said opposed faces of said rails when the chair is in assembled position, a locking block secured in one of said rails and projecting therefrom, and a slot in said yoke for receiving said block when the chair is in assembled position.
